[57] CLAIM

The ornamental design for a package for compact disk, as shown and described.

DESCRIPTION

FIG. 1 is a front, top, and left side perspective view of a package for compact disk showing our new design, with top panel bent forward;

FIG. 2 is a left side elevational view of the structure of FIG. 1, with top panel bent forward;

FIG. 3 is a right side elevational view of the structure of FIG. 2;

FIG. 4 is a front elevational view of the structure of FIG. 2;

FIG. 5 is a rear elevational view of the structure of FIG. 2;

FIG. 6 is a top view of the structure of FIG. 2;

FIG. 7 is a bottom plan view of the structure of FIG. 2; and, FIG. 8 is a front, top, and left side perspective view thereof, with the package almost completely closed.
